C Inventor
WILLIAM J. GEIST
By W. Hallawell
His Attorney

UNITED STATES PATENT OFFICE

WILLIAM J. GEIST, OF MAPLEWOOD, MISSOURI

SPOUT

Application filed October 28, 1930. Serial No. 491,667.

This invention relates to a spout and relates more particularly to a spout suitable for use on containers for holding household commodities, etc. It is a general object of the invention to provide a simple, practical, and improved spout construction.

This application is a continuation in part of my co-pending application entitled spout construction, serial Number 312,477, filed

10 October 15, 1928.

It is an object of the invention to provide a spout that may be applied to a container at any time during its manufacture or after it has been fully formed and sealed and ready

15 for shipment.

Another object of the invention is to provide a spout of the character mentioned that is extremely simple and inexpensive to manufacture and that may be formed of a single

20 body or piece of material.

It is another object of the invention to provide a spout that may be quickly and easily sprung into position in an opening in a container so that it is dependably and effectively attached to the container. It is a feature of the invention that the spout may be applied to a container without special attaching or securing parts.

It is another object of the invention to provide a spout construction that embodies an improved hinge connection between the spout and the container whereby the spout may be operated between open and closed positions without any undesirable dropping or lateral

35 movement of the spout.

A further object of the invention is to provide a simple one-piece spout of the character mentioned that may be formed of light material and yet be strong and durable.

40 A particular object of this invention is to provide a spout of the character mentioned in which the resiliency of the material involved is utilized to permit of attaching the spout to the container.

45 Another object of the invention is to provide a spout construction of such formation as to be capable of being sprung into place or operating position with reference to the container to be freely operable yet dependably and effectively attached to the container.

Other objects and features of my invention will be best and more fully understood from the following detailed description of a typical form and application of the invention, throughout which description reference will be had to the accompanying drawing, in which:

Fig. 1 is an exterior view of a typical container illustrating the spout provided by this invention applied thereto. Fig. 2 is a side elevation of the container showing the spout in the open position. Fig. 3 is a view of the container taken as indicated by line 3—3 on Fig. 2. Fig. 4 is an enlarged sectional view of a portion of the container showing the spout in the partially operated position. Fig. 5 is an enlarged detailed sectional view of the hinge portion of the construction illustrating the spout in the open position. Fig. 6 is a view similar to Fig. 5 illustrating the spout in the closed position. Fig. 7 is a front view of the spout illustrating the manner of applying the spout to the opening in the container. Fig. 8 is a front view similar to Fig. 7 showing the spout in the applied position. Fig. 9 is an enlarged plan view of a portion of the container illustrating the opening in which the spout is to be arranged, and Fig. 10 is a form or blank from which the container may be formed.

The spout provided by this invention may be applied to and is useful in connection with the various types of containers. The spout is well suited for use on containers for handling various household commodities, such as salt, etc. The present invention is not primarily concerned with the type of container on which the spout is to be used nor with the material to be handled. For the purpose of example and illustration I have shown the spout applied to a typical container 10, it being understood that the invention is not to be taken as restricted to the particular application of the invention illustrated throughout the drawing.

The container 10 may have cylindrical side walls 11 and a flat end or top 12. In the case illustrated the top 12 has a flange 13 at its perimeter for engaging over the end portion of the side walls 11. The top 12 and the side

walls 11 may be separable or may be permanently joined, and the entire container may be sealed and ready for use before the spout is applied thereto, it being a feature of the invention that the spout may be applied to or removed from the container 10 at any time. The container 10 may be formed of any suitable material. For example, it may be formed of a suitable paper, or the like. The spout may be applied to or mounted in a discharge opening in any suitable part of the container. For the purpose of example, the top wall 12 is illustrated as having an opening A for the reception of the spout. The shape and the proportioning of the opening A are more or less dependent upon the character of the container and the commodity or material to be handled. In the case shown the opening A is substantially rectangular, having straight parallel side walls or edges 14. One end wall 20 or edge 14 is provided with a tongue 17 which projects into the opening A. The tongue 17 may be integral with the top 12 of the container, and is preferably in the same plane as the top. The tongue 17 is spaced from the side walls 14 of the opening by notches 18 which are provided to receive sides of the spout as will be hereinafter described.

The spout provided by the present invention includes, generally, a bottom part 20 and spaced side parts 21. The spout is preferably formed of a material having a certain degree of resiliency. For example, it may be formed of certain classes of metal or paper. In accordance with the invention the spout may be formed of a single piece or blank of material such as is illustrated in Fig. 9 of the drawing.

The bottom part 20 is preferably of substantially the same configuration as the opening A. In the preferred form of the invention the bottom part 20 is shaped and proportioned so that it closes the opening A when the spout is in the closed position illustrated in Figs. 1 and 6 of the drawing. In the case shown the bottom part 20 is of the same width as the opening A and extends between its opposite ends. The tongue 17 operates to prevent the passage of the bottom 20 through the opening A when the spout is in the closed position, and a tab 22 may be provided at an end of the bottom part 20 to overlie the top 12 of the container at the end of the opening. The tab 22 may be formed so that it may be readily grasped or engaged to operate the spout between the open and closed positions. The bottom part 20 is preferably flat so that it lies substantially flush with the top 12 when in the down position.

The sides 21 of the spout join and project downwardly or inwardly from the opposite side edges of the bottom part 20. Referring particularly to Fig. 10 of the drawing, the sides 21 may be formed by bending the blank along the lines B so that they project from

the opposite edges of the bottom part 20. The sides 21 are preferably alike in shape and are segmental in form, each having a curved outer edge 23 joining the bottom part 20 at its tab end and a substantially straight edge 24 joining the bottom part 20 at its hinge end and extending to the curved edge 23. The sides 21 may be substantially parallel or they may diverge outwardly toward the bottom 20 so that their outer faces may slidably engage the side edges 14 of the opening A.

The sides 21 extend into the notches 18 at the tongue 17. A lug 25 is provided on each straight edge 24 adjacent its inner end. A notch 26 is provided at the inner edge of each lug 25 to cooperate with a notch 18 to form a hinge connection between the spout and the container. The notches 26 are shaped to effectively cooperate with the notches 18, and their outer or lower walls may be cut away or beveled as shown at 27 in the drawing. The tongue 17 extends between the sides 21 when the spout is in position in the opening A to properly space the sides and to center the spout in the opening. In accordance with the invention a hinge bar or web 28 extends between and connects the two lugs 25. The upper edge of the web 28 joins the extreme ends of the lugs 25 and the web is channeled or bent to have a longitudinal groove 30 in its one side and two angularly related faces 32 and 42 on its other side. The face 42 is adapted to seat against the under side of the top 12 when the spout is in the open position as clearly illustrated in Fig. 5 of the drawing. The face 32 engages the under side of the top 12 when the spout is in the closed position as illustrated in Fig. 6 of the drawing. The corner or edge 31 between or joining the faces 32 and 42 is adapted to pivot on the lower side of the top 12 when the spout is operated between the open and closed positions.

In the preferred form of the invention the faces 32 and 42 are at substantially 90° to one another and the face 42 is wider than the face 32. The edge 31 is preferably straight so that it has effective engagement with the top 20. It will be apparent how the web 28 reinforces the spout and prevents undesirable shifting or movement of the spout when it is operated between the open and closed positions. The web 28 acts to properly space the sides 21 and to prevent distortion or bending of the lugs 25. When the spout is formed of a single body of material the lugs 25 and the web 28 may be formed of a portion C of the blank by first forming a transverse slot 33 between the lines B and then bending outwardly the portion of the material outwardly of the slot at an angle to form the channeled web 28 and the beveled walls 27 in the notches 26.

The notches 26 and lugs 25 are held in their proper cooperation with the notches 18 by the curved edges 23 of the sides 21 which fit

the opening A so that the spout is held against longitudinal movement in the opening. The curved edges 23 are curved about points at or adjacent the axis of pivotal connection of the 5 spout with the container. The spout may be proportioned so that the curved edges 23 frictionally engage or approximately engage the end 15 of the opening A so that the notches 26 are retained in cooperation with the 10 notches 18 at all times. If desired, and the nature of the material of which the container is formed permits, the curved edges 23 of the sides may frictionally engage or cut into the end 15 of the opening to retain the spout 15 in the open or closed positions until deliberately moved.

In the preferred form of the invention the sides 21 of the spout may be shaped or proportioned so that they normally bear outwardly against the sides 15 of the opening A to maintain a suitable amount of friction between the spout and the container. This is desirable as it is convenient to have the spout such as to stay in a position to which it may be moved. The sides 21 diverge outwardly toward the bottom 20 so that the portions 70 of the sides adjacent the bottom 20 are somewhat wider apart than the other parts of the sides when the spout is in open position. This formation of the sides 21 causes the spout to remain in the open position unless deliberately operated therefrom.

If the wall 12 of the container is formed of paper, or the like, a reinforcing plate 60 may be applied to the wall at the opening A.

In accordance with the invention one or both of the sides 21 are provided with stops 36 on their outer sides. It is through the action of the stops that the spout is prevented from being displaced outwardly from the opening. The stops 36 project laterally outward in opposite directions from the sides 21 to engage the lower side of the top 12 of the container when the spout is in the open position to limit the outward movement of the spout. The stop projections 36 may be provided at or adjacent the point of joinder of the edges 23 and 24. The stops 36 are adapted to be passed into the opening A when the spout is applied to the container by springing the sides 21 inwardly or toward one another as illustrated in Fig. 7 of the drawing. When it is desired to mount the spout in the opening, its hinge end is first passed into the opening A so that the notches 26 cooperate with the notches 18 and the tongue 17 projects through the slot 33 between the web 28 and the edge of the bottom 20. The sides 21 may then be sprung together so that the stops 36 may be passed into the opening A. The resiliency of the sides 21 may automatically return the sides to their slightly divergent positions where the stops 36 are adapted to engage the lower side of the top 12 to limit the outward pivoting of the spout. It is to be

noted that the web 28 holds the hinge end of the sides 21 against inward movement or bending when their outer portions are sprung together to pass the stops 36 into the opening A.

It is believed that the operation and utility of the spout construction provided by this invention will be readily apparent from the foregoing detailed description. It is to be noted that the invention provides a spout which may be easily and quickly applied to a container after it is completed and filled. The spout may be formed of a single piece of material and is particularly inexpensive of manufacture. The hinge bar or web 28 materially reinforces the hinge portion of the spout and aids in preventing inward and outward shifting of the hinged end of the spout when it is operated. Further, the web 28 strengthens the sides 21 and holds them normal or perpendicular to the bottom part 20. The web also adds to spring or resiliency of the sides 21, so that they return to their proper positions after being sprung toward one another to pass the stops in the opening A.

Having described only a typical preferred form of my invention, I do not wish to limit myself to the specific details set forth, but wish to reserve to myself any changes or variations that may appear to those skilled in the art or fall within the scope of the following claims.

Having described my invention, I claim:

1. A spout for a container wall having an opening including, a bottom, sides projecting from the bottom to extend into the opening, and means forming a hinge connection between the spout and the container wall including lugs projecting from the sides, notches in the spout at the lugs to cooperate with an end of the opening, and a web extending between the lugs for engaging the under side of the container wall.

2. A spout for a container having an opening with spaced notches in one end forming a tongue projecting into the opening, which includes, a bottom, sides projecting from the bottom, means forming a hinge connection between the spout and the container including lugs projecting from the sides, there being notches at the junction of the lugs with the sides to cooperate with the notches in the opening, and a web extending between the lugs for engaging the under side of the tongue, and means for limiting the outward pivoting of the spout in the opening.

3. A spout for a container having an opening including, a bottom, sides projecting from the bottom to extend into the opening, and means forming a hinge connection between the spout and the container including, lugs projecting from the sides, there being notches between the lugs and the sides to cooperate with an end of the opening, and a web com-

necting the lugs adapted to pivot on the interior of the container wall during operation of the spout.

4. A spout for a container having an opening with notches in one end forming a tongue projecting into the opening which includes, a bottom, sides projecting from opposite edges of the bottom to extend into the opening, lugs on the sides having notches to cooperate with the notches in the end of the opening to form a hinge connection between the spout and the container, and a web extending between the lugs for engaging the under side of the tongue, there being a slot between the bottom and said web passing the tongue.

5. A spout for a container having an opening with spaced notches in one end, which includes a bottom, sides projecting from the bottom to extend into the opening, a lug on each side, there being notches in the lugs to cooperate with the notches in the end of the opening to form a hinge connection between the spout and the container, and a web connecting the lugs adapted to engage the under side of the wall of the container.

6. A spout for a container having an opening with spaced notches in one end, which includes a bottom, sides projecting from the bottom to extend into the opening, a lug on each side, there being notches in the lugs to cooperate with the notches in the end of the opening to form a hinge connection between the spout and the container, and a web connecting the lugs and having a face to lie against the under side of the wall of the container when the spout is in the closed position.

7. A spout for a container having an opening with spaced notches in one end, which includes a bottom, sides projecting from the bottom to extend into the opening, a lug on each side, there being notches in the lugs to cooperate with the notches in the end of the opening to form a hinge connection between the spout and the container, and a web connecting the lugs and having a face to lie against the under side of the wall of the container when the spout is in the closed position, and a face to lie against the under side of the wall of the container when the spout is in the open position.

8. A spout for a container having an opening with spaced notches in one end, which includes a bottom, sides projecting from the bottom to extend into the opening, a lug on each side, there being notches in the lugs to cooperate with the notches in the end of the opening to form a hinge connection between the spout and the container, and a web connecting the lugs and having a pivot edge to cooperate with the under side of the wall of the container when the spout is operated.

9. A spout for a container wall having an opening including, a bottom, sides projecting

from the bottom to extend into the opening, means for forming a hinge connection between one end of the spout and the container wall including, lugs projecting from the sides, there being notches in the spout between the lugs and the sides to cooperate with an end of the opening, and a web extending between and connecting the lugs, to cooperate with the interior of the container wall, and stops projecting outwardly from the sides, the sides being resilient and adapted to be sprung inwardly toward one another to positions to pass the stops through the opening.

10. A spout for a container wall having an opening including, a bottom, sides projecting from the bottom to extend into the opening, means for forming a hinge connection between one end of the spout and the container wall including, lugs projecting from the sides, there being notches in the spout between the lugs and the sides to cooperate with an end of the opening, and a channeled web extending between the lugs to pivot on the interior of the container wall, and a stop projection projecting laterally outward from a side adjacent the other end of the spout, the said side being resilient and adapted to be sprung inwardly to a position to pass the stop projection through the opening, the web acting to brace the sides so that the sides normally bear outwardly against the walls of the opening.

11. A spout for a container having an opening with spaced notches in one end, which includes a bottom, sides projecting from the bottom to extend into the opening, a lug on each side, there being notches in the lugs to cooperate with the notches in the end of the opening to form a hinge connection between the spout and the container, and a web connecting the lugs and having a face to engage the wall of the container when the spout is in the closed position and a face to engage the wall of the container when the spout is in the open position and having an edge between the said faces to cooperate with the wall of the container when the spout is operated between the open and closed positions.

In witness that I claim the foregoing I have hereunto subscribed my name this 18th day of August, 1930.

WILLIAM J. GEIST.
